UNITED STATES PATENT OFFICE

JAMES B. OLIVER, OF SEWICKLEY, PENNSYLVANIA.

WIRE-OILING DEVICE.

SPECIFICATION forming part of Letters Patent No. 296,440, dated April 8, 1884.

Application filed February 1, 1884. (No model.)

To all whom it may concern:

Be it known that I, JAMES B. OLIVER, of Sewickley, in the county of Allegheny and State of Pennsylvania, have invented a new and useful Improvement in Wire-Oiling Devices; and I do hereby declare the following to be a full, clear, and exact description thereof.

In the manufacture of barbed fence-wire it is customary to oil the wire before it is put through the barbing-machine, so that it shall pass through the guides of the latter with minimum friction. The usual way of oiling is to dip the hank or coil into a bath of oil or to pour the oil over it. The objection to this plan is that the oil is not perfectly applied and the waste is very great, as the oil remains on the surfaces and in the interstices of the inner coils and cannot be dripped or drained out, but remains until the coil is unwound, when it drops or runs down, and is lost. Moreover, the waste oil falls on the floor and other surrounding objects and makes them very dirty and disagreeable, as well as increases fire-risks. Attempts have been made to apply the oil by passing the wire through an oiler containing cotton or wool waste, yarn, or similar material saturated with oil; but these attempts have not been attended with perfect success, for the reason that the oil-saturated material was caused by the movement of the wire to become compacted into a closely-knit and nearly if not entirely impenetrable mass, which wedged in around the wire and prevented its free passage through the oiler. My invention is designed to obviate this trouble and to effect the proper oiling of the wire.

To enable others skilled in the art to make and use my invention, I will now describe it by reference to the accompanying drawings, forming a part of this specification, in which—

Figure 1 is a vertical longitudinal section of my wire-oiling device. Fig. 2 is a vertical cross-section on the line $x-x$, Fig. 1. Fig. 3 is a view of part of the device.

Like letters of reference indicate like parts in each.

The case a , which contains the oil-applying medium, is preferably of cylindrical shape, 50 having a tapering end, a' , provided with a hole for the exit of the wire b . The other end is closed by a cap, c , screwed or otherwise re-

movably fastened thereto. This cap has a central opening for the entrance of the wire, and a conical or concave face for convenience in guiding the end of the wire into the hole. Placed inside of the case a is a removable perforated cylinder, d , which is used for convenience in packing the oil-applying medium and of putting it in and removing it from the case a . It is also useful because it allows the oil to pass down between it and the sides of the case a , and so gain access to the oil-applying medium on all sides through the perforations. On the upper side of the case a is an oil cup 65 or trough, e , which communicates with the interior of the case by means of holes or slots e' .

The material I use in the oiling-box for applying the oil to the surface of the wire is preferably sawdust; but I can use any other material—such as fine wood shavings, used by upholsterers for packing, comminuted sponge, cork, or other material which is capable of being saturated with the oil, and of being compressed without forming a compact impenetrable mass. 70 The cylinder d , being filled or packed with sawdust, is placed in the box a , the end a' of which is filled with wool waste, or other suitable material, to prevent the wire from dragging the sawdust through with it. The oil passing 80 down through the holes e' and around the cylinder d enters the perforations and saturates the sawdust. The wire b passes lengthwise through the box a . The sawdust being saturated with oil, the latter is applied evenly and 85 properly to the wire. Having a wiping action, the sawdust removes all surplus oil from the surface of the wire and gives it a smooth and uniform coating of oil. I have particularly mentioned sawdust as the preferred material. 90 I do not limit myself thereto, but include also other materials, some of which are named, having the same or equivalent properties.

If desired, some wool may be placed at or 95 about the middle as well as at the outer end of the box, to aid in keeping the sawdust in position.

The cylinder d may be dispensed with; but I prefer it for the reasons stated.

I do not limit myself to a cylindrical or any other particular form for the box a and its inner casing d .

I do not claim the construction of the oiler,

as that was the invention of John Stubbe, and forms the subject-matter of an application of even date by him for Letters Patent thereon.

What I claim as my invention, and desire 5 to secure by Letters Patent, is—

1. The method of oiling wire, consisting in passing it through oil-saturated compressed sawdust or similar material, substantially as and for the purpose described.

10 2. A wire-oiler consisting of a suitable case

containing oil-saturated sawdust or similar material, and having wool or similar material surrounding the wire-exit opening, substantially as and for the purposes described.

In testimony whereof I have hereunto set my 15 hand.

JAMES B. OLIVER.
